UNITED STATES PATENT OFFICE.

JOHN C. CROMWELL, OF CLEVELAND, OHIO.

POWER-HAMMER.

1,318,359.

Specification of Letters Patent. Patented Oct. 14, 1919.

Application filed July 28, 1917. Serial No. 183,290.

To all whom it may concern:

Be it known that I, JOHN C. CROMWELL, a citizen of the United States, residing at Cleveland, in the county of Cuyahoga and 5 State of Ohio, have invented a new and useful Improvement in Power-Hammers, of which the following is a full, clear, and exact description, reference being had to the accompanying drawings, forming part of 10 this specification, in which—

Figure 1 is a view partly in end elevation and partly in transverse vertical section showing a power hammer embodying my invention with the guide rollers adjusted 15 to a relatively wide-open position; and

Fig. 2 is a section on the line II—II of Fig. 1.

My invention has relation to power or forging hammers and is designed to provide 20 a hammer having guiding means mounted thereon of simple and effective character for coöperation with the work piece being operated upon.

The nature of my invention will be best 25 understood by reference to the accompanying drawing, in which I have shown a preferred embodiment thereof, and which will now be described.

In these drawings, the numeral 2 designates 30 the frame of the hammer having the supporting legs 2^a. 3 designates the hammer proper. 4 is an anvil base, and 5 an anvil block mounted thereon.

In accordance with my invention, I provide 35 the hammer with laterally adjustable guides at each side of the work piece, together with means for adjusting the same toward and away from such piece. In the preferred form, these guides consist of vertical rollers 6, which depend from and are journaled to slide blocks or carriages 7, which are mounted for transverse movement on the guides 8. I preferably provide two of these guide rollers at each side of the 40 work piece, substantially as shown. Any suitable means may be provided for their adjustment whereby they may be moved laterally toward and away from the center line of the anvil. It will be understood that 45 in the arrangement shown, there are four of these guide rollers, there being one pair at each side of the longitudinal center of the anvil and one roller of each pair being in advance of the anvil and the other roller 50 behind the anvil.

In the drawings, I have shown electric motors 9, one for each pair of the guides, these motors being mounted on the frame of the hammer preferably at opposite sides and connected by suitable gearing 10, with 60 right and left hand threaded adjusting rods 11, which engage nuts 12, on the slides or carriage 7. By actuating these motors, the slides together with the guides can be adjusted under complete control, as may be 65 desired. The guides form effective means for coöperation with the work piece, while being properly positioned on the anvil block.

I claim:

1. Forging apparatus, comprising a hammer frame, a hammer mounted thereon, guides on said frame, carriages mounted for transverse movement on said guides, and a plurality of work-guiding members carried by and depending from said carriages, substantially as described. 70

2. Forging apparatus, comprising a hammer frame, a hammer mounted thereon, guides on said frame, carriages mounted for transverse movement on said guides, and a plurality of work-guiding members carried by and depending from said carriages, together with means for actuating said carriages to move them toward and away from the vertical center line of the hammer; substantially as described. 80

3. Forging apparatus, comprising a hammer frame, a hammer mounted thereon, guides on said frame, carriages mounted for transverse movement on said guides, and a plurality of work-guiding members carried by and depending from said carriages, there being a plurality of the guiding members at each side of the center of said hammer; substantially as described. 90

4. Forging apparatus, comprising a hammer frame, a hammer mounted thereon, transversely extending guides on the frame, slide blocks or carriages mounted on the guides, and depending work-guiding rolls carried by said blocks or carriages; substantially as described. 100

5. Forging apparatus, comprising a hammer frame, a hammer mounted thereon, guides on said frame, carriages mounted for transverse movement on said guides, and a plurality of work-guiding members carried by and depending from said carriages, there being a plurality of the guiding members at each side of the center of said hammer 105 110

and power means for simultaneously actuating the carriages; substantially as described.

6. In forging apparatus, the combination 5 with an anvil, of a hammer frame, a hammer mounted on said frame over said anvil, and work-guiding members mounted on said frame and depending therefrom at opposite

sides of the anvil, together with means for moving said members toward and away 10 from the center line of the anvil; substantially as described.

In testimony whereof, I have hereunto set my hand.

JOHN C. CROMWELL.

Copies of this patent may be obtained for five cents each, by addressing the "Commissioner of Patents, Washington, D. C."
